CLAIM

The ornamental design for a steamer insert apparatus, as shown.

DESCRIPTION

A device for insertion into a kitchen pot for steaming a hot dog bun or the like, while providing access for insertion and removal of a hot dog or the like.

FIG. 1 is a perspective view of a steamer insert apparatus.

FIG. 2 is a top plan view of a steamer insert apparatus.

FIG. 3 is a bottom plan view of a steamer insert apparatus.

FIG. 4 is a front elevational view of a steamer insert apparatus; and,

FIG. 5 is a side elevational view of a steamer insert apparatus.
